APPARATUS FOR TREATING STEEL

Frederick W. Pitts, Detroit, Mich., assignor to
Michigan Steel Corporation, Detroit, Mich., a
corporation of New Jersey

Application March 5, 1929, Serial No. 344,544

5 Claims. (Cl. 15—102)

This invention relates generally to apparatus for treating steel and more particularly to a scrubber for cleaning the steel prior to shipping the latter.

5 While the invention is capable of many and diversified uses, nevertheless it finds particular utility in the manufacture of steel sheets of the type used in constructing automobile bodies and the like wherein it is highly desirable that the 10 sheets be free from all foreign matter such as stains prior to applying the desired finish thereto.

In the present day manufacture of steel sheets, the stains and other foreign matter are removed therefrom by a process commonly known in the 15 trade as wash pickling wherein the sheets are placed in a bath of sulphuric acid solution. This operation has been found objectionable from various standpoints among which are; first, the comparatively great expense involved in treating each sheet with sulphuric acid solution; second, the labor and time required in handling each 20 sheet separately; and third, the comparatively large area of floor space and tanks necessary for the installation of such a process.

25 It is therefore one of the primary objects of this invention to replace the expensive operation of wash pickling and accompanying apparatus therefor, with a more compact machine which not only automatically operates to thoroughly 30 clean the sheets, but to cool and dry the same as well.

Much of the commercial value and acceptability of the invention is attributed to the simplicity of the scrubber and the expeditious manner 35 in which the same operates to thoroughly clean and dry the sheets, thereby rendering possible materially increased production as well as reducing the cost of manufacture of each sheet.

A further advantageous feature of the present 40 invention resides in the adaptability of the scrubber to a rolling machine, thus permitting the metallic sheets to be moved by the rolling machine directly into the scrubber without additional handling of the sheets.

45 Other objects and advantages of the present invention reside in the peculiar construction of the scrubber illustrated and about to be described.

50 In the drawings:

Figure 1 is a side elevation of a scrubber constructed in accordance with my invention.

Figure 2 is a top plan view of the construction shown in Figure 1 with certain parts removed 55 for the sake of clearness.

Figure 3 is a sectional view taken on the line 3—3 of Figure 1.

Figure 4 is a sectional view taken on the line 4—4 of Figure 2.

Figure 5 is a sectional view taken on the line 5—5 of Figure 2.

Figure 6 is a sectional view taken on the line 6—6 of Figure 1.

Figure 7 is a sectional view taken on the line 7—7 of Figure 2.

Referring now to the drawings, it will be noted that there is illustrated a scrubbing machine 10 having a base 11 and having a pair of side frames 12 and 13 secured to opposite sides of the base by means of the bolts 14. Each of the side frames 12 and 13 is provided with a pair of vertically extending guideways 15 and 16 respectively arranged in alignment with each other. As shown in Figure 1 each of the guideways receives a pair of bearing blocks 17 which in turn form journals for the transversely extending shafts 18 and 19. The shafts 18 are preferably journaled in the upper bearing blocks 17 while the shafts 19 are journaled in the lower blocks.

Secured to each of the shafts 18 and 19 are the rolls 20 which are normally yieldably maintained in engagement with each other by means of the coil springs 21. The latter are arranged within the upper portions of the guideways 15 and 16 and have the lower ends bearing upon the upper bearing blocks 17 and the upper ends thereof engaging followers 22 slidably engaging the side walls of the guideways. The tension exerted upon the upper bearing blocks 17 by the springs is adjustable by means of screws 23 threadedly engaging the cap members 24 and engaging the followers 22. The cap members 24 are secured to the upper ends of the frame members and function to close the upper ends of the guideways 15 and 16. Thus it will be noted that the scrubber is provided with two sets of pressure rolls, one set adjacent the receiving end of the machine and designated by the numeral 23 and the other set adjacent the discharge end of the machine and designated by the character 24.

As shown in Figure 2 of the drawings, the shafts 19 carrying the lower rolls 20, are rotated by means of a suitable prime mover 25 secured to a support 26 which in turn is secured to the side frame 13. In detail the motor 25 is connected through suitable reduction gearing 27 to a countershaft 28 which is journaled upon the support 26 and is connected to the shafts 19 by means of the train of gears 29. Thus from 55

the foregoing it will be apparent that the lower rolls of each set are power driven and owing to their frictional engagement with the upper rolls, the latter will also be rotated.

For effecting the cleaning operation, I provide a pair of upper and lower headers 30 and 31 respectively. As shown in Figure 2 of the drawings the headers extend between the side frames 12 and 13 intermediate the two sets of pressure rolls and are secured to the side frames upon opposite sides of the path of travel of the sheets, by means of the bolts 32. The headers are preferably cast in one piece and are provided with substantially flat base portions 33 having outwardly projecting hollow portions 34 intermediate the side edges and extending substantially the full length of the base portions. The hollow portions 34 are adapted to contain the cleaning fluid and communicate at one end with the supply pipes 35 and at the opposite end with the return pipes 36. For ejecting the cleaning fluid from the hollow portions aforesaid upon the sheets passing therebetween, the headers are provided with longitudinal spaced passages 37 extending from the hollow portions and through the base portions 33. The base portions 33 of the headers are provided at the ends thereof with inwardly projecting tapered flanges 38 co-operating with each other to form a tapered passage 39. This passage is arranged in direct alignment with the path of travel of the sheets and functions to guide the same from one set of the rolls 20 to the other set. The passage 39 is preferably tapered toward the discharge set of rolls 24' so as to accurately guide the sheets into engagement therewith. Thus a dual function is attributed to the headers as the latter in addition to ejecting a cleaning fluid upon the sheets, accurately guide the latter during their travel through the machine.

For guiding the sheets into engagement with the first set of pressure rolls 20 a suitable table or conveyor 40 is provided adjacent the receiving end of the scrubber. This conveyor comprises a pair of side frame members 41 and a plurality of spaced shafts 42 extending transversely of the frame members and having the opposite ends thereof journaled within the frame members 41. Mounted upon the shafts 42 in spaced relation to each other are a plurality of disks or wheels 43 for supporting the metallic sheets in alignment with the path of travel of the latter through the presser rolls.

The operation of the machine up to this point is as follows: A metallic sheet is placed upon the table 40 and moved between the first set of presser rolls 23'. The latter immediately grip the sheet and move the same into the passage 39 formed by the headers 30 and 31 and during its travel through this passage, it is subjected to a bath of cleaning fluid, such for example as steam discharged through the ports 37 formed in the headers. As shown in Figure 1 the sheets are compelled to travel between the headers 30 and 31 and as a consequence steam or the like will be discharged through the ports 37 upon opposite sides of the sheets. After the cleaning operation just described, the sheet is discharged from the passage 39 between the second set of presser rolls 24' which operate to grip the sheet and discharge the same upon a conveyor 42 to be more fully hereinafter described. Both sets of rolls 20 are preferably although not necessarily, formed of rubber or some similar material so that these rolls, in addition to con-

veying the sheets through the machine also function to remove or in effect, wipe any moisture from the sheets.

In the event that steam is used to clean the plates it is desirable to provide some means for exhausting the steam immediately after the same is discharged from the headers so as to prevent the excess steam from condensing upon the sheets. This is accomplished in the present instance by extending a hood 43 over the upper header 30 and connecting the hood to a suitable exhaust fan (not shown), through the medium of a conduit 44.

The conveyor 42 heretofore referred to for moving the sheets away from the scrubber may be of any suitable construction but is herein shown as comprising a plurality of spaced shafts 45 journaled in suitable bearings 46 which in turn are secured to the spaced blocks 47 extending upwardly from the frame member 48. Each of the shafts 45 are provided with a plurality of spaced sprocket wheels 49 and are connected to each other by means of chains 50 extending around the sprockets and forming a moving table for supporting and conveying the sheets to their destination. As shown particularly in Figures 1 and 2, the conveyor is actuated by a drive shaft 51 extending transversely of the scrubber adjacent the discharge end of the same and journaled in bearings 52 formed upon extensions 53 of the side frames 12 and 13. The shaft 51, like the shafts 45, is provided with a series of sprocket wheels arranged in alignment with the sprockets 49 and connected to the latter by means of the chains 50. Journaled upon one end of the shaft 51 is a sprocket wheel 55 connected through the medium of a chain 56 to a sprocket wheel 57 secured to one end of the shaft 19 in the second set of presser rolls 24'. Thus it will be apparent that rotation is imparted to the shaft 51 by the prime mover 25.

While the second set 24' of presser rolls are designed to wipe the condensate from the sheets as the latter pass therethrough, nevertheless additional apparatus is provided for thoroughly drying and cooling the sheets so that the same will not sweat when stacked for shipment. This apparatus comprises an air drier indicated generally by the character 58 and operable to direct a current of air against opposite sides of the sheet as the latter is conveyed from the presser rolls 24' to their destination. The drier includes a suitable blower (not shown) for forcing air into the conduit 57' which, as shown in Figure 1, is connected to upper and lower headers 58 and 59 respectively, by means of the conduits 60. The headers 58 and 59 are supported above and below the path of travel of the sheets by means of a suitable frame construction 61 and are provided with a plurality of lateral extensions 62 having longitudinally extending slots 63 therein for directing the air toward opposite sides of the sheets during movement of the latter along the conveyor.

In Figure 1 of the drawings the scrubber 10 is shown in combination with a cold rolling machine 64. This machine is of conventional design and, as diagrammatically illustrated in the above figure, comprises a frame 65 and a pair of presser rolls 66 journaled in the frame and driven in any suitable manner (not shown). Extending directly above the upper roll is a suitable water header 67 operable to discharge a stream of water upon the upper roll and thereby provide a wet

pass for the sheets. The scrubber in this event is secured to the frame 65 of the rolling machine in such a manner that the pass between the two sets of presser rolls 20 will be in direct alignment with the pass between the rolls 66 so that upon passing a sheet through the rolls 66, the same will be moved by the latter along the conveyor 40 into direct engagement with the first set 23 of presser rolls 20. The distance between the latter presser rolls and the rolls 66 is substantially equal to the length of the sheets to be treated so that it is not necessary to impart rotation to the conveyor 40. With an arrangement of this latter character, it is essential, in order to eliminate undue wearing of the presser rolls 20 to accurately synchronize the speed of the latter to the speed of the rolls 66. This is accomplished by varying the speed of the prime mover 25, which in the present instance is a variable speed electric motor. Thus from the above it will be apparent that the scrubber is readily adapted for use with a cold rolling machine and is capable of operation therewith without the assistance of additional labor as the rolling machine in addition to rolling the sheets, feeds the same directly into the scrubber.

Thus from the foregoing it will be noted that the present invention offers the possibility of eliminating the wash pickling operation and accompanying mechanism heretofore considered necessary in the manufacture of metallic sheets of the character set forth and renders possible, replacing this operation and apparatus therefor, with a more compact and simpler machine capable of not only thoroughly cleaning the sheets but to dry the same as well. It will further be noted that the herein described machine is thoroughly automatic in operation and as a consequence reduces the amount of labor to a minimum.

40 What I claim as my invention is:

1. In a machine for cleaning metallic sheets, the combination of a pair of presser rolls for advancing the sheets, a pair of headers operable to eject a cleaning fluid upon opposite sides of the sheets during their travel through the machine, and a second pair of presser rolls cooperating with the rolls aforesaid to move the sheets through the machine and further operable to remove the cleaning fluid from the sheets, said headers having their ends provided with inwardly projecting tapered flanges engaging and cooperating to space the headers whereby to define a passage for guiding the sheets into engagement with the second pair of rolls, said passage contracting toward the discharge end thereof.

2. In a machine for cleaning metallic sheets, the combination of a frame, spaced pairs of presser rolls mounted upon the frame for conveying the sheets through the machine, spaced headers arranged between said spaced pairs of rolls upon opposite sides of the path of travel of the sheets for ejecting a cleaning fluid thereon, said headers having substantially flat inner

faces and having cooperating tapering portions for spacing the headers apart to provide a tapered passage for accurately guiding the sheets from one pair of rolls to the other.

3. In a machine for cleaning metallic sheets, the combination of a frame, spaced pairs of presser rolls mounted upon said frame for conveying the sheets through the machine, and means upon said frame between the spaced pairs of rolls aforesaid for ejecting a cleaning fluid upon opposite sides of said sheets, said means including headers arranged upon opposite sides of the path of travel of the sheets and adjacent each of said pairs of rolls and cooperating to form a passage for accurately guiding the sheets from one pair of rolls to the other, said headers having flat base portions provided with reinforcing ribs at the outer faces thereof and provided with flat surfaces at the inner faces thereof.

4. In an apparatus for treating metallic sheets, a traction unit adapted to be arranged adjacent to and in communication with a rolling machine for receiving the sheets and applying traction thereto before discharge from the latter, spaced headers arranged upon opposite sides of the path of travel of the sheets and in juxtaposition to said traction unit for ejecting cleaning fluid upon the sheets, said headers having substantially flat inner faces fashioned with apertures for ejecting said cleaning fluid and having cooperating tapering portions for spacing the headers apart to provide a tapered passage for guiding the sheets, a second traction unit arranged adjacent to the discharge end of said headers and operable to remove the cleaning fluid from the sheets, and means for synchronizing the speed of said traction units with the speed of the rolls of the rolling machine.

5. In an apparatus for treating metallic sheets, a combined scrubber and traction unit adapted to be arranged adjacent to and in communication with a rolling machine for receiving the sheets and applying traction thereto before discharge from the latter, said scrubber and traction unit including yieldable power actuated rolls for engaging, cleaning and advancing the sheets, a pair of headers arranged upon opposite sides of the path of travel of the sheets and adjacent to said scrubber and traction unit for ejecting cleaning fluid upon the sheets, said headers having substantially flat inner faces provided with means for ejecting said cleaning fluid and having cooperating tapering portions for spacing the headers apart to provide a tapered passage for guiding the sheets, a second scrubber and traction unit arranged adjacent to the discharge end of said headers and operable to remove the cleaning fluid from the sheets, and a variable speed drive for said scrubber and traction units whereby the speed of the same may be synchronized with the speed of the rolls of the rolling machine.

FREDERICK W. PITTS.
